UNITED STATES PATENT OFFICE.

ARTIE C. CARLSON, OF VALPARAISO, INDIANA, ASSIGNOR, BY MESNE ASSIGNMENTS,
TO THE NORTHERN TRUST COMPANY AND HAROLD H. ROCKWELL AS TRUSTEES.

DESIGN FOR A TOY BOAT.

Application filed February 11, 1927. Serial No. 20,717. Term of patent 7 years.

To all whom it may concern:

Be it known that I, ARTIE C. CARLSON, a citizen of the United States, residing at Valparaiso, in the county of Porter and State of Indiana, have invented a new, original, and ornamental Design for Toy Boats, of which the following is a specification, reference being had to the accompanying drawing, forming a part hereof.

The figure in the drawing is a perspective view of a toy boat showing my new design.

I claim:

The ornamental design for a toy boat, substantially as shown.

ARTIE C. CARLSON.
